UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

OPEN BEARING.

1,096,190.

Specification of Letters Patent. Patented May 12, 1914.

Original application filed June 14, 1911, Serial No. 633,021. Divided and this application filed September 19, 1913. Serial No. 790,805.

To all whom it may concern:

Be it known that I, CHARLES H. NORTON, a citizen of the United States, residing at Worcester, in the county of Worcester and State of Massachusetts, have invented a new and useful Open Bearing, of which the following is a specification.

This invention relates to an open bearing and forms a division of applicant's prior application Serial No. 633,021, filed June 14, 1911.

One object of my invention is to provide an open bearing so constructed that a shaft or roll supported upon said bearing may be ground while thus supported, the parts of the bearing being so arranged that they do not interfere with the grinding operation.

Another object of my invention is to provide improved devices for adjusting the supporting members of the open bearing.

To the accomplishment of the objects above referred to, the invention comprises the features and combinations of parts hereinafter described and more particularly pointed out in the appended claims.

A preferred form of my invention is shown in the drawings in which—

Figure 1 is an end view of an open bearing; Fig. 2 is an enlarged sectional view taken along the line 2—2 of Fig. 1; Figs. 3 and 4 are end and side elevations respectively of the setting device; and Fig. 5 is an enlarged plan view of the means for clamping the setting device in position; Fig. 6 is a detail view of the locking bolt for securing the head of the setting device upon its support; and Fig. 7 is a detail view of the device for clamping the scale rod in position.

In the embodiment of my invention herein shown, the bearing comprises a frame 10 supporting a plurality of radially adjustable bearing members 11. The frame 10 may be mounted upon any suitable support 12 and when found desirable may be arranged for longitudinal adjustment along a guide 13, being held in adjusted position by a bolt 14. The bearing members 11 are arranged to be adjusted to a predetermined circumference and to support the rotating roll or shaft R thereon.

As shown in Fig. 1, the bearing members 11 are disposed in two series of radially ar-

ranged slots 14, the uppermost member of the front series being placed in a plane substantially below the center of the rotating shaft so that the grinding wheel W may contact with the shaft along its horizontal diameter. The uppermost member of the rear series, however, is arranged in a higher plane than the corresponding member of the front series and is adapted to counteract the thrust of the grinding wheel. Each bearing member as shown in Figs. 1 and 2, is provided with an arc-shaped bearing surface 55 upon its upper side and with a pair of oppositely inclined supporting surfaces upon its under side. Arranged within each radial slot 14 is a pair of oppositely disposed wedge-shaped blocks 15 mounted upon a compound screw 16. The screw 16 is provided with a collar 17 fitting a recess 18 in the frame 10, by which it is restrained from longitudinal movement. The screw 16 is also provided with an extension 19 adapted 60 to receive a wrench by which it may be adjusted.

In order that the bearing surfaces 11 may be accurately set to any desired circumference, a setting device is provided comprising a frame 20 adapted to be secured to the guide 13 by a clamping lever 21. The frame 20 carries a plate 22 upon which is rotatably mounted a head 23 supporting a horizontal sleeve 24. The head 23 is pivoted upon a stud 25 and may be retained in either one of two diametrically opposed positions by a spring-pressed locking bolt 26, as shown in Fig. 6. Within the sleeve 24 is rotatably mounted a stud 27 having a head 28 within 75 which is slidably mounted a graduated rod 29. The rod 29 may be retained in adjusted position within the head 28 by the clamping device shown in detail in Fig. 7 and comprising a threaded sleeve 30 having a threaded stud 31 secured therein, a sleeve 32 loosely mounted on said stud 31 and a nut 33 threaded on said stud and provided with a knurled head 34 by which the same may be turned to clamp the rod 29 between the clamping members 30 and 32. One side of the rod 29 may be slabbed off, as at 35, to receive the graduations, and the head 28 may be provided with a block 36 secured by a screw 37, the block coacting with the flat side of 80 the rod 29 to prevent the same from turn-

ing, and the upper edge of said block serving as a reference surface by which to read the scale.

Inspection of the drawings will show that 5 the axis of the stud 27 is maintained in fixed relation to the guide 13 and that consequently, by setting the scale rod 29 to any desired radius and swinging the same upon the stud 27, the rod may be brought in contact successively with each of the bearing members and that by use of the adjusting screw 16 each bearing member may be radially adjusted to the circumference determined by the rod.

Having thus described my invention, it will be obvious that many changes and modifications therein can be made by one skilled in the art without departing from the spirit and scope thereof, and I do not wish to be 20 limited to details herein disclosed, but

What I do claim is:—

1. An open bearing comprising a frame and two sets of arc-shaped members carried thereby, the uppermost support of the front 25 set being in a plane substantially below that of the uppermost support in the rear set.

2. An open bearing comprising a frame, a plurality of arc-shaped supports mounted in radial slots in said frame, wedge-shaped 30 blocks underlying said supports, and means for adjusting said blocks.

3. An open bearing comprising a frame, and a plurality of arc-shaped supports mounted in radial slots in said frame, each 35 support having an inclined surface on its

back and an adjusting wedge engaging the same.

4. An open bearing comprising a radially slotted frame, a plurality of arc-shaped supports mounted in the slots in said frame, the 40 rear side of each support being formed with a pair of inclined surfaces, wedge-shaped blocks fitted in oppositely disposed pairs in said slots under said supports, and a compound screw threaded into each pair of 45 blocks for adjusting said support.

5. An open bearing comprising a radially slotted frame, a plurality of arc-shaped supports mounted in the slots in said frame, the rear side of each support being 50 formed with a pair of inclined surfaces, wedge-shaped blocks fitting in oppositely disposed pairs in said slots under said supports, and a compound screw having an integral collar received in a recess in said 55 frame and having right and left-hand screw-threads engaging threaded openings in a pair of said blocks, said screw being also provided with an extension by which it may be turned to move said blocks simultaneously 60 and to thereby adjust one of said supports radially.

In testimony whereof I have hereunto set my hand in the presence of two subscribing witnesses.

CHARLES H. NORTON.
